PRESS GUIDING GIB

Bertrand Japikse, Reiffton, Pa.

Application October 22, 1946, Serial No. 704,854.

6 Claims. (Cl. 308—3)

1

This invention relates to a press and more particularly to a guiding arrangement for maintaining a platen of the press in a definite and fixed path during reciprocating movements thereof.

An object of the invention is the provision, in a press, of improvement in guiding means so that during and upon the making of adjustments at or in the guiding means, full surface-bearing relationships will be positively established between relatively movable parts.

Another object of the invention is the provision, in a press, of an improved guiding means which will circumvent the turning of a platen thereof about its vertical axis.

The above and numerous other objects will become apparent from the succeeding description which is to be considered together with the accompanying drawings; the latter of which illustrate merely an exemplification of the invention and is not to be considered as a limitation.

Reference, generally, now is made to the drawings wherein:

Figure 1 is a general arrangement, more or less in outline, of a press embodying the present invention.

Figure 2 is a schematic horizontal sectional view taken along the lines 2—2 of Figure 1, looking in the direction of the arrows.

Figure 3 is an enlarged horizontal sectional view showing in detail the structure within the circle in Figure 2 and marked "A."

Figure 4 is an enlarged horizontal sectional view showing in detail the structure within the circle in Figure 2 and marked "B."

Figure 5 is a front elevational view of the structure shown in Figure 4 and is taken along lines 5—5 of Figure 4, looking in the direction of the arrows.

Figure 6 is a front elevational view of the structure shown in Figure 3 and is taken along the lines 6—6 of Figure 3 looking in the direction of the arrows.

Referring now in detail to the drawings, wherein like reference characters indicate like parts, the numeral 1 is employed to designate a press having as components thereof features of the present invention. Considered generally, the press, illustrated as one of the hydraulic type comprises a base 2 having upstanding from the respective ends thereof spaced housings 3 which support a head 4. Movable vertically by means of a main ram 5 is a platen 6.

The present invention is concerned solely with guiding the platen along a definite and fixed or

2

predetermined path during its reciprocating or vertical service movements. It is believed that since a fine degree of craftsmanship must be exercised in machining or forming the guiding surfaces along which a platen is arranged to move, nothing is gained by such exercise of skill unless the components carrying the surfaces are arranged in such a manner that after the press has left the manufacturer and gone into service, proper and accurate adjustments may be made by a person not too skilled in the maintenance of such machinery. Also it is to be noted before proceeding with the detailed description of the invention that the components carrying the 10 guiding surface should be arranged in such a manner so as to insure a sliding fit of the guiding surfaces and also that related guiding surfaces be at all times juxtaposed across their widths with no chance of them being so related as to 15 be angularly disposed to one another. A relationship other than purely parallel between related guiding surfaces not only will cause a line as opposed to a surface contact between such surfaces thus soon rendering such surfaces inadequate for the purpose intended but also it will be possible to turn the platen about a vertical axis however so slightly to render the entire press incapable of performing the work with the fine degree of accuracy for which it was originally designed.

In order to incorporate, in the press, all of the good features hereinabove set forth and eliminating all of the undesirable features also set forth above each housing has at one inner corner thereof 20 of a basic alignment face 8 which extends vertically and longitudinally of the press and is carefully and accurately machined because this face on each housing forms the basic plane to which all other surfaces hereinafter referred to, are relative. Suitably mounted upon each basic alignment face is a liner 9 primarily designed of a predetermined thickness of bronze preferably to function as a replaceable wear plate. Each housing also carries an inward facing face 10 which need not necessarily be machined to a great 25 degree of accuracy other than it is important that this face 10 present an accurate and true plane face extending vertically and transversely of the press. This latter face 10 is substantially a continuation of its related basic face and is disposed desirably at ninety degrees or at a true right angle thereto. The face 10 is further provided with a removably secured, vertically extending, inwardly facing wear plate 11 preferably formed 30 of bronze for purposes which are apparent.

Outstanding from the platen at a predetermined portion spaced outwardly of the press from a related housing is a wall, barrier, lug or abutment 12 which may or may not be formed integrally with the platen. Each wall extends vertically and is substantially parallel with a related inwardly facing face 10. Intermediate each abutment and its associated end of the platen there is provided an outwardly exposed, vertically directed face 13 desirably formed or machined true so that it is perpendicular to an adjacent face 10 on the housing and its related bronze wear plate. This outwardly exposed face is desirably coextensive with a related abutment but need not necessarily be made so. Positioned between each abutment and its related housing corner is a rear shoe or guiding gib 14 having an inwardly exposed face 15 arranged to bear intimately against a companion or coplanar face 13. Main holding bolts or anchor means 16 are spaced in vertical alignment along each guiding gib to hold the latter in a predetermined or fixed position. Assisting the anchor means are a series of aligned auxiliary holding bolts 17 also functioning as a means by which the related guiding gib is retained in fixed position on the platen. The main holding bolts and auxiliary holding bolts extend through suitable apertures 16a and 17a respectively in a related guiding gib and which are desirably made greater in diameter than that necessary for the accommodation of the occupying bolts so that while the bolts remain fixed relative to the platen the guiding gib is thus arranged preferably to be shifted in one plane only toward or away from the next or adjacent housing or the adjacent abutment for the purpose to be hereinafter made apparent. Each rear shoe is provided with a vertically extending horizontally disposed, inwardly exposed surface 18 which is machined true and smooth and is desirably disposed in a plane parallel to and at a predetermined exact distance from a companion inwardly exposed face 15. This surface 18 is so arranged and disposed to bear against and be in sliding engagement with a correspondingly disposed surface or rubbing surface 9a on a related liner 9. In other words, the surface 18 is in sliding contact with the liner 9 when the shoe face 15 and platen face 13 are in bearing relation with one another and thus a plurality of longitudinally spaced surfaces are arranged to assist in guiding the platen along a fixed vertical path and assist in preventing the platen from shifting, wobbling or moving transversely of the press from a true vertical path.

Forming in substance a continuation of the surface 18 of each rear shoe or guiding gib is a vertically extending, transversely disposed, outwardly exposed surface 19 which upon certain adjustment being made is arranged to slidably engage a contiguous liner 11 to assist in preventing a longitudinal shifting action of the platen. Extending through suitably drilled vertically aligned holes 20 in each abutment are a series of pulling or drawing set screws 21 which extend into suitably tapped openings in a related guiding gib so that any manipulation of the drawing set screws will move the affected guiding gib toward the companion abutment. Each guiding gib or rear shoe is also provided with a plurality of pushing set screws 22 with desirably a pair spaced about or in vertical alignment with each drawing set screw. The heads 23 of the

pushing set screws are arranged in abutting relation with a companion abutment so that, the pushing set screws permitting, a proper manipulation of the pushing set screws will result in a related rear guiding gib being urged toward an associated housing.

A mechanic unskilled in the art of properly adjusting a press may easily adjust a rear side of a press embodying that portion of the invention hereinabove described by simply letting up on the main and auxiliary holding bolts 16 and 17. This being done the pushing set screws or pulling set screws are then manipulated so that the distance between a butt of one rear guiding gib and its related barrier indicated by the character "X" is equal to the distance between a butt of the other rear guiding gib and its companion barrier indicated by the character "W" (see Figure 2). When these distances are equal and the surfaces 19 are in sliding contact with their liners, the main and auxiliary holding bolts are tightened to lock the rear guiding gibs in their thus set locations. The pulling set screws are then properly tightened to relieve the holding bolts of any sheer stresses to which they might be subjected in service.

Referring now to what might properly be considered as the front of the press each front inner corner of each housing is provided with a diagonal, vertically disposed surface 24 set at an angle to rubbing surfaces 9a and 11a of the liners 9 and 11 respectively. Each diagonal surface may properly be considered as being inclined or exposed in a direction toward the interior and outside of the press. Removably secured to each diagonal surface is a bronze liner 25 having a brushing surface 25a thereof parallel to and preferably coextensive with a related diagonal surface.

Outstanding from the platen in a direction opposed to the direction of the abutments 12 but preferably in transverse alignment therewith are a pair of longitudinally spaced, vertically extending shoulders, partitions or abutments 26. The shoulders may be made or formed integral with the platen or, if desired, may be made as separate components and firmly secured to the platen. Interposed between each shoulder and its adjacent inclined surface is an outwardly exposed vertically extending face 27 which is desirably machined or formed true and smooth and parallel with the face 13. Arranged in intimate contact with and surface bearing relation with each face 27 is a front shoe or guiding gib 28 held in a predetermined or fixed position on the platen by means of main tie bolts 29 arranged in vertical alignment intermediate the transverse limits of a related guiding gib. Spaced from the main tie bolts toward an associated shoulder is a series of aligned auxiliary tie bolts 30 which assist in maintaining a gib in a fixed position against stresses to which it will be subjected in service. The main and auxiliary tie bolts extend through suitable apertures 29a and 30a respectively which are of greater diameter than the related tie bolts so as to incorporate in the structure a degree of adjustability which will be brought out more clearly hereinafter. Each front guiding gib is provided with an inclined somewhat inwardly exposed surface 31 arranged to be in sliding contact with the brushing surface 25a of the inclined liner 25. Spaced at predetermined intervals and vertically along each shoulder is a series of drawing screws 32 which extend freely through the related shoulder and are in threaded engagement

with accommodating and horizontally aligned holes in an adjacent front shoe. Spaced vertically on each side of a drawing screw is a pushing screw 33 in threaded engagement with the front shoe and having a head 33a bearing against a related shoulder.

With the rear guiding gibs adjusted as previously set forth the tie bolts are loosened and the screws 32 and 33 are manipulated so that the distance between the butts of the front guiding gibs and shoulders are equal as indicated by the characters "Y" and "Z." The operator need only equalize the dimensions "Y" and "Z" and observe that the front guiding gib inclined surfaces 31 are in intimate contact with the brushing liner surfaces 25a and further observing that the rear shoe surface 18 is in sliding contact with a related liner rubbing surface 9a. It will be here noted that a proper manipulation of the screws 32 and 33 will not only cause the platen to be centered properly between the housings longitudinally of the press but will also cause the platen to be centered properly transversely of the press. Having accomplished the above settings the main and auxiliary bolts are tightened and so far as the proper positioning of the platen is concerned the press is ready to be operated with assurance that the platen will move only along a true predetermined vertical axis.

From the above it will be noted that various changes and alterations may be made to the illustrated and described specie of the invention without departing from the spirit of the invention and scope of the appended claims.

I claim:

1. In a press having a housing member and a platen member arranged to move relative thereto, the combination of, guiding surfaces disposed normal to one another carried by said housing at one corner thereof, a guiding gib mounted on said platen member, said guiding gib having surfaces normal to one another and each arranged to contact one of said housing guiding surfaces, adjustable means for shifting said gib in one plane only relative to said platen and moving one of said gib surfaces toward and away from the contacting of said housing guiding surfaces, a single guiding surface carried by said housing at another corner thereof, said single surface being disposed diagonally to said normally disposed surfaces, a second guiding gib mounted on said platen member opposite from said first named guiding gib, a surface carried by said second guiding gib being arranged to contact said diagonally disposed surface, and adjustable means for shifting said second gib in one plane only relative to said platen and moving said surface of said second gib toward and away from the contacting of said housing guiding surfaces.

2. In a press having a housing member and a platen member arranged to move vertically relative to said housing member, the combination of, guiding surfaces disposed normal to one another carried by one of said members at one corner thereof, a guiding gib adjustably mounted on the other of said members and having surfaces in intimate contact with each of said guiding surfaces, said guiding gib being adjustable in one plane only for moving one of said gib surfaces toward and away from the contacting of said guiding surfaces, a single guiding surface carried by another corner of one of said members, said single guiding surface being disposed diagonally

to said normally disposed surfaces, and a second guiding gib adjustably mounted on another of said members and having a surface complementary to and engaging said diagonally disposed single surface, said second guiding gib being adjustable

in one plane only relative to said another of said members for moving said complementary surface toward and away from said single surface and therethrough another of said surfaces of said first guiding gib toward and away from said contacting of said first guiding surfaces.

3. In a press having a housing and a platen arranged to move vertically relative to said housing, transversely spaced parallel faces on said platen, normally disposed surfaces at one corner of said housing, a diagonal surface at another corner of said housing, a pair of transversely spaced guiding gibs mounted on said platen and having faces in intimate contact with said spaced parallel faces, surfaces disposed normal to one another carried by one of said guiding gibs and being in sliding relation with said housing normally disposed surfaces, a diagonal surface carried by the other of said guiding gibs and being in sliding contact with said housing diagonal surface, and adjustable means for shifting each of said gibs relative to said platen and moving each of said gib surfaces toward and away from the contacting of said housing surfaces.

4. In a press having a housing and a platen arranged to move vertically relative to said housing, transversely spaced parallel faces on said platen, normally disposed surfaces at one corner of said housing, a diagonal surface at another

corner of said housing disposed at an angle to said normally disposed surfaces, a pair of transversely spaced guiding gibs, faces on said guiding gibs in bearing relation with said platen parallel faces, one of said guiding gibs having surfaces

arranged to slidably engage said normally disposed surfaces, and another of said guiding gibs having a surface arranged to slidably engage said diagonal surface, and adjustable means for shifting each of said gibs relative to said platen

and moving each of said gib surfaces relative to the engaging surfaces of said housing.

5. In a press having a housing and a platen arranged to move vertically relative to said housing, transversely spaced vertically extending fixed faces on said platen, surfaces disposed at right angles to one another at one corner of said housing, a diagonal surface at another corner of said housing and being disposed at an angle to said right angle surfaces, a pair of transversely spaced

guiding gibs mounted on said platen, said guiding gibs having faces in intimate contact with said platen faces, one of said guiding gibs having surfaces disposed at right angles to one another each confronting and arranged to slide along

one of said right angle surfaces of said housing, and another of said guiding gibs having a diagonal surface confronting and arranged to slide along said housing diagonal surface, and adjusting means for shifting each of said gibs relative

to said platen only in the direction horizontally of said vertically extending fixed faces and moving each of said gib surfaces toward and away from the confronting of said housing surfaces.

6. In a press having a housing and a platen arranged to move vertically relative to said housing, transversely spaced vertically extending fixed faces on said platen, means outstanding from said platen perpendicular to said fixed faces, surfaces disposed at right angles to one another at one corner of said housing, a single surface at an

other corner of said housing and being disposed at an angle to said right angle surfaces, a pair of transversely spaced guiding gibs mounted on said platen, adjusting means associated with said outstanding means and guiding gibs for moving said guiding gibs toward or away from said outstanding means, said guiding gibs being held firmly against said platen faces, one of said guiding gibs having surfaces disposed at right angles to one another and arranged to slide along said housing right angle surfaces, and another of said guiding gibs having a diagonal surface and arranged to slide along said housing single surface.
